EX 1

M. Townsend,

Design for the Border of Shawls

Patented Octo. 14. 1862.

N° 1663.

Matthew Townsend

In presence of

John M. Dashiell -
John F. Hopkins.

UNITED STATES PATENT OFFICE.

MATTHEW TOWNSEND, OF CHELSEA, MASSACHUSETTS.

DESIGN FOR THE BORDER OF SHAWLS, &c.

Specification forming part of Design No. 1,663, dated October 14, 1862.

To all whom it may concern:

Be it known that I, MATTHEW TOWNSEND, of Chelsea, in the county of Suffolk and State of Massachusetts, have invented or produced a new and original Design for Knit Shawls; and I do hereby declare that the following is a full and exact description of the same, reference being had to the accompanying drawing.

In the drawing, (marked A,) a garment termed a "Sontag" is represented; but my design does not relate to the general form or outline, but to the knit border, which may be applied to scarfs, capes, cloaks, mantles, or other articles. The border is knit by ma-

chinery and has raised folds or plaits B B B extending across the under part or main body of the border c c c, thus producing a new effect or appearance not heretofore known or used. This raised border may be left in loops as it is knit, or it may be cut or otherwise varied upon its surface.

What I claim is—

The knit border having raised or plaited lines or folds B B extending across it, as represented in the accompanying drawing.

MATTHEW TOWNSEND.

In presence of—

JOHN M. BATCHELDER,
SAML. BATCHELDER, Jr.
